UNITED STATES PATENT OFFICE.

ARNOLD VON SCHRENK, OF TUCKAHOE, NEW YORK.

MECHANICAL MOVEMENT FOR DOORBOLTS AND THE LIKE.

Application filed October 25, 1922. Serial No. 596,750.

To all whom it may concern:

Be it known that I, ARNOLD VON SCHRENK, a citizen of the United States, residing at Crestwood, Tuckahoe, county of Westchester, and State of New York, have invented certain new and useful Improvements in Mechanical Movements for Doorbolts and the like, of which the following is a specification, reference being had to the accompanying drawing, illustrative of one particular embodiment of my invention.

This invention relates to mechanical movements involving in particular the control of potential power and its application by the exertion of a relatively small fraction of the power in order to control the application of the potential energy. It involves the further development of the invention of the principle set forth in my Patent No. 1,291,664 granted January 14, 1919, and has for its particular object the provision of a mechanical movement of simple construction, durability, ease of operation and reliability, and in certain respects features of construction for the special application of such mechanical movement.

This application provides more particularly for the use of the invention in or on structures such as refrigerator doors. In this and similar structures it is desired to apply considerable force to actuate certain intermittent operating devices as, for example, the locks on a refrigerator door which must be tightly closed and therefore requires a predetermined and considerable pressure. While different operators may exert a varying pressure or fail to apply sufficient force for the proper actuation of the structure, this invention provides for mechanical parts to exert the predetermined pressure at all times with only a slight and relatively small power application on the part of the operator. Thus the force closing the doors, or similar operation, does not depend upon any varying effort on the part of different operators or the same operator, and still more, a single movement well within the limits of any operator's power results in the same power application from the stored potential energy member with uniformity and at all times.

In the case of refrigerator doors, a plurality of bolts at different parts of the periphery of the door can all be actuated by a single power application from a single

unit of predetermined potential power, and the control of the actuation may be effected by a single lever requiring but a small fraction of effort compared with the power actuating the bolt or bolts.

In the accompanying drawings forming a part hereof,—

Fig. 1 is a front elevation of a refrigerator door showing the mechanical movement to operate a single bolt, the cover of the mechanism being removed.

Fig. 2 is a fragmentary view, front elevation, of a door showing the mechanism controlling two bolts with a single operating lever.

Fig. 3 is a fragmentary view showing the mechanical movement on a large scale with the casing removed, shown in detail.

Fig. 4 is a cross-section of the latch or bolt and bolt socket of Fig. 3, on a larger scale.

Referring to the figures, 1 is a floating lever which operates on a movable fulcrum 3, shaped like a roller, the position of which can be varied by shifting the rod 4, to which it is attached. A spring 2 is connected to one end of the floating lever 1. The other end of spring 2 is connected to a second lever 5, which turns on a fixed pin 6. Spring 2 is attached to the two levers 1 and 5 in such a way as to be under compression in the arrangement of elements herein shown. But with another arrangement it might be under tension. The ends of levers 1 and 5 opposite to spring 2 are connected together by a link 7. Link 7 moves in a guide 15, and its end is formed into a door catch 16 having a taper end which engages with a recessed fitting 17 rigidly secured to the door jamb 20. An operating handle 10 carries a toothed sector 11, which meshes with a rack 12 attached to the fulcrum-carrying rod 4. The rod 4 moves on rollers 13, 13, and is held in place by fixed guides 14, 14. The floating lever 1 is prevented from displacement by a link 8, which turns on a fixed pin 9.

As the forces exerted at the opposite ends of spring 2 are of equal value at all times, it is obvious that this system of levers and links will be in equilibrium if the movable fulcrum 3 is moved to a position such that the arms of floating lever 1 will have the same ratio as the arms of lever 5. This equilibrium position of the fulcrum is de-

noted by the line $a-a$. If the fulcrum 3 is moved below the equilibrium line $a-a$, the arm of lever 1 acted upon by the spring 2 will be shortened, and the force of spring 2 operating with the longer arm of lever 5 will cause link 7 to move to the right. When the handle 10 is moved down, the sector 11 drives rack 12 and rod 4 in a downward direction, thus moving fulcrum 3 below the equilibrium line $a-a$, and causing the power of the spring 2 to be exerted in such a manner as to move link 7 to the right. This will shove the taper end of catch 16 into the recess of fitting 17, thus pressing 15 the door 19 tightly against the door jamb 20.

The entire mechanical movement is assembled on a plate 18, which is bolted to the door 19. The shaft of handle 10 and sector 20 11 may extend through the door, so that the device may be operated from either side of the door.

A spring 21 may be arranged to operate with the rod 4 to keep the fulcrum 3 normally below the equilibrium line $a-a$, and thus hold the catch 16 in the closed position, unless the handle 10 is raised. In this way the door and fastener may be made self closing.

If desired, the taper end 16 may be replaced by a roller 26, cooperating with a suitable fitting 27 attached to the door jamb, as shown in Fig. 2. In the case of large and heavy doors for which it is desired to have more than one fastening, the link 8 may be replaced by a bell crank 22, which operates in connection with a rod 23, bell crank 24 and rod 28, working in the guide 25, to push the catch 26 into the fitting 27, as shown in Fig. 2. The number of these fastenings may be multiplied as much as is desirable.

In the application of my invention, other forms of springs may be used and other sources of power may be employed, such, for instance, as compressed air, hydraulic power, steam, magnetism, and so on, and other arrangements of the various elements may be made, within the scope of my invention. I 50 do not confine myself to the exact construc-

tions herein shown and described, but what I claim and desire to secure by Letters Patent is:

1. A mechanical movement for control of intermittent operating mechanism comprising a reciprocating member and a supporting guide therefor, a potential energy element connected therewith and intervening levers including a floating lever and a shiftable fulcrum therefor, means of support for control of said fulcrum and means to automatically move said fulcrum in one direction and manually shift the same in the opposite direction. 55

2. A mechanical device for actuating door bolts and the like including a power-delivering element and means for applying the energy thereof to press said bolt, said means including a floating lever and a shiftable fulcrum therefor and manually operated 70 means to control the application of said energy. 65

3. A mechanical device for reciprocating a door bolt or similar device, comprising a mechanical potential power element, a system of balance levers associated therewith including one lever and an associated shiftable fulcrum, means for shifting said fulcrum in one direction and means for automatically returning said fulcrum in the opposite direction to insert the bolt or like member. 75 80

4. A mechanical movement for operating a door-closing device and the like, including a potential energy element, a lever with a fixed fulcrum, a floating lever, a movable fulcrum, and means for shifting said movable fulcrum. 85

5. A mechanical device for operating door bolts and the like, including a potential 90 source of power, a lever with a fixed fulcrum, a floating lever, a movable fulcrum for said floating lever, means for shifting said movable fulcrum, and connecting linkage. 95

In testimony whereof, I have signed my name to this application, this 30th day of March, 1922.

ARNOLD VON SCHRENK.
